Term of patent 14 years

(Cl. D14—3)

FIG. 1.

FIG. 2.

FIG. 3.

FIG. 4.

FIG. 5.

FIGURE 5 is a side elevation view thereof when used as a cart with the wheels down.

The dominant features of my design reside in the portions shown in full lines.

I claim:

The ornamental design for a combination golf club holder and a wheeled easel mount, as shown and described.
